UNITED STATES PATENT OFFICE.

DURBIN RICHARDSON AND CHARLES N. JACOBY, OF ROCHESTER, NEW YORK, ASSIGNEES
TO RICHARDSON CORPORATION, OF ROCHESTER, NEW YORK, A CORPORATION OF
NEW YORK.

APPARATUS FOR DISPENSING BEVERAGES.

1,278,219.

Specification of Letters Patent. Patented Sept. 10, 1918.

Application filed October 12, 1917. Serial No. 196,293.

To all whom it may concern:

Be it known that we, DURBIN RICHARDSON and CHARLES N. JACOBY, both of Rochester, in the county of Monroe and State of New York, have invented certain new and useful Improvements in Apparatus for Dispensing Beverages; and we do hereby declare the following to be a full, clear, and exact description of the same, reference being had to the accompanying drawings, forming a part of this specification, and to the reference-numbers marked thereon.

Our invention relates to dispensing beverages such as are usually charged with carbonated water when served, and is intended to provide an improved apparatus, particularly adapted for dispensing root-beer. Our chief purpose is to afford an apparatus that insures thoroughly charging the beverage with the requisite amount of carbonic acid by maintaining a considerable supply in a charged state, which insures a thorough intermingling of the gas and causes the beverage to be dispensed in an extremely rich-tasting, creamy and pleasing condition. A further purpose of the invention is to provide an apparatus which is sanitary, and can be readily controlled and cleansed, and which also requires a minimum amount of floor space. To these and other ends the invention consists in certain improvements and combinations of parts, all as will be herein-after more fully described, the novel features being pointed out in the claims at the end of the specification.

The drawing is a vertical sectional view, with parts in elevation, illustrating a practical embodiment of the invention.

The structure disclosed includes a housing or cabinet 1 which receives a carbonating machine, designated generally at 2, and the detailed structure of which forms no part of the present invention as it is a standard equipment which can be purchased and is utilized for carbonating water. 3 is a tank containing carbonic acid and connected with the carbonating machine by means of the pipe 4 for a purpose that will appear more clearly in the following description.

Arranged and supported upon the top of the housing 1 is a container which is preferably in the exterior form of a barrel and is designated generally by 5. The container carries a removable cover 6, and arranged within the container is a removable liquid

chamber 7 into which the beverage is initially supplied upon removing the cover 6. Surrounding the liquid chamber 7 is an ice chamber 8, which is separated from the outer portion of the container by means of a wall 60 of heat insulating material and an inner lining 10.

The beverage is carried from the liquid chamber 7 by a siphon, one leg of which extends into the liquid chamber and nearly to the bottom thereof, as designated by 11, while the opposite end of the siphon leads to the carbonating machine 2 through a suitable feed pump 12. The siphoning of the beverage from the liquid chamber to the carbonating machine is of material advantage, as it eliminates any liquid tight joints through the chamber, and by removing the short leg of the siphon, permits the chamber 7 to be removed and readily cleaned. 75

The ice chamber and coils therein, to be referred to presently, can likewise be readily cleansed by removal of the chamber 7, so that the parts can be kept in a thoroughly sanitary condition without great difficulty. 80 The beverage being supplied to the carbonating machine by the pump 12, it is there charged with carbonic acid supplied from the tank 3. The gas mixes thoroughly with the beverage and places it under pressure, in which state it issues from the carbonating machine through the pipe 13. The last mentioned pipe 13 extends from the housing 1 upwardly into the container 5 and through the ice chamber 8 in the form of coils 14, 90 whence it leads to the dispensing faucet 15. The ice chamber serves the double function of cooling the contents of the chamber 7 before being charged with carbonic acid, and also maintains the mass in the coils 14 cold 95 after having been charged in the carbonating machine. This insures the beverage being drawn off from the faucet 15 in a thoroughly cold state, and so charged and agitated by the action of the gas that it comes out in a 100 condition that is foamy or creamy throughout, due largely to the fact that a considerable mass of the beverage is held under pressure and the entire body of liquid between the carbonating machine and the dispensing faucet is gas charged. 16 is an overflow pipe for the ice chamber. 105

In operation, the beverage mixture is poured into chamber 7, after removing the cover 6. In the case of root-beer, the mix- 110

ture consists of the root extract, simple syrup, and water. The beverage is forced into the carbonating machine by the pump 12, where it is charged with carbonic acid. 5 It then passes under pressure, to the coils 14, and is drawn off through the faucet 15 in a cold and thoroughly carbonated state.

Such an apparatus is especially adapted for dispensing root-beer and similar beverages, and it is believed new to carry a prepared beverage through a carbonating machine, and maintain a considerable mass of the beverage under pressure and fully charged with carbonic acid. The construction disclosed may be varied in different respects without departing materially from the scope of the invention, and it is the intention to cover any modified arrangements embodying a container provided with a liquid chamber and an ice chamber and located in the described relation to a carbonating machine.

We claim as our invention:

1. A beverage dispensing apparatus comprising a housing, a carbonating mechanism located in the housing, a container supported upon the housing, a liquid chamber arranged within the container, a discharge faucet located on one side of the container, a conducting pipe leading from the liquid chamber to the carbonating mechanism, and a conducting pipe leading from the carbonating mechanism through said container and to the discharge faucet.

2. A beverage dispensing apparatus comprising a container, a liquid chamber ar-

ranged within the container, a discharge faucet located on one side of the container, a carbonating mechanism, a conducting pipe leading from the liquid chamber to the carbonating mechanism, and a conducting pipe leading from the carbonating mechanism through said container and to the discharge faucet. 40

3. A beverage dispensing apparatus comprising a housing, a carbonating mechanism located in the housing, a container supported upon the housing, a liquid chamber arranged within the container, a discharge faucet located on one side of the container, 45 an ice compartment within the container surrounding said liquid chamber, a conducting pipe leading from the liquid chamber to the carbonating mechanism, and a conducting pipe leading from the carbonating mechanism through said container and ice compartment to the discharge faucet. 50

4. A beverage dispensing apparatus comprising a carbonating mechanism, a container, a liquid chamber removably arranged within the container, a discharge faucet located on one side of the container, an ice compartment within the container surrounding said liquid chamber, a siphon conductor leading from said chamber to the 60 carbonating machine, and a conducting pipe leading from the carbonating machine through said container and ice chamber to the dispensing faucet. 65

DURBIN RICHARDSON.
CHARLES N. JACOBY.
